UNITED STATES PATENT OFFICE

HAGE W. HUCKNALL, OF ELYRIA, OHIO, ASSIGNOR TO THE AMERICAN LACE MFG. CO., OF ELYRIA, OHIO, A CORPORATION OF OHIO

DESIGN FOR LACE EDGING

Application filed June 1, 1931. Serial No. 40,040. Term of patent 3½ years.

To all whom it may concern:

Be it known that I, HAGE W. HUCKNALL, a citizen of the United States, residing at Elyria, in the county of Lorain and State of Ohio, have invented a new, original, and ornamental Design for Lace Edging, of which the following is a specification, reference being had to the accompanying drawing, forming part thereof. The figure is a plan view of a section of lace edging, showing my new design, the repeat unit of which is contained between the two vertical dot and dash lines.

I claim:

The ornamental design for lace edging substantially as shown and described.

HAGE W. HUCKNALL.
